UNITED STATES PATENT OFFICE.

AUGUST ERNST KARL GUSTAV HARTMANN, OF HAMBURG, GERMANY.

PRINTING-MACHINE.

1,132,844.

Specification of Letters Patent. Patented Mar. 23, 1915.

Application filed January 28, 1915. Serial No. 4,949.

To all whom it may concern:

Be it known that I, AUGUST ERNST KARL GUSTAV HARTMANN, a subject of the King of Prussia and German Emperor, residing at Hamburg, Germany, have invented certain new and useful Improvements in Printing-Machines, of which the following is a specification.

The present invention refers to a printing machine for producing prints of small size more particularly for printing addresses on envelopes and other small writings, such as bills, memorandums, cards, letters and the like. In printing machines of this class, 10 the type plates are carried along in a known manner one after the other by a feeding device consisting of endless chains with studs or tappets which push the type mechanism along up to the printing plates and further 15 on until they are cast off.

The object of the invention is to produce sharp and clean printings by a speedy operation. To obtain this object a peculiar circulating pressure roll is arranged in such 20 manner, that it can move over the article to be printed, when the latter is placed on the type plate, and thus produce the print. This pressure roll has the effect of bringing the paper in contact with every part of the 25 set of types or of the type plate, so that a failure of any letters or parts of letters in printing is impossible and an equal and sharp print is produced, which is very distinct and can be easily read, even if the 30 types are small.

To insure that the types are well printed on all parts of the type plate, the circulating pressure roll is so arranged, that its distance from the axis of revolution can be yieldingly 35 reduced. Together with this pressure roll a circulating gripper is operated in such manner, that immediately after the print is carried out the paper or other article is caught hold of and thrown off. In order to 40 prevent the paper being smutted by the ink ribbon the paper is raised by an automatically controlled frame when the paper is caught by the gripper.

In the drawings a machine is shown constructed according to this invention.

Figure 1 is a sectional elevation, Fig. 2 a cross section of the machine, Fig. 3 is a sectional plan of a device for raising the frame, and Fig. 4 is a plan showing the ink ribbon 45 in combination with the above named frame.

In the construction shown the type plates are piled up in a reservoir or shaft *b*, which is arranged vertically and preferably removably at one end of the machine. Below this shaft there is the table *c* on which the type plates *a* can be moved along by the aid of studs or tappets *d*¹, mounted on the endless chains *d* and engaging the edges of the plates *a* which projects laterally beyond the table *c*. The chains *d* run over sprocket 50 wheels or drums *e* and *f* which can be driven from a crank *g*, operatively connected with a shaft *h* by the gears *g*¹ and *g*². On the shaft *h* there is a sprocket wheel *h*¹, which is connected by a chain *h*² with a sprocket 55 wheel *i*¹ mounted on the tube or hollow shaft *i*. This tube surrounds the shaft *k*, which is journaled below the table *c* and is adapted to be connected with the hollow shaft *i* by the clutch *k*¹. At one end the 60 shaft *k* carries a mutilated bevel gear *k*² adapted to engage a second bevel gear *k*³ mounted on a shaft *l*, carrying the sprocket wheel *f*. Thus by rotating the crank *g* the shaft *l* is rotated when the clutch *k*¹ is 65 thrown into gear and the chains *d* are driven in the direction of the arrow A.

A bracket *m* is fastened to the shaft *h* and at the free end of the bracket two arms *m*¹ are pivotally connected between which the pressure roll *n* is journaled. A spring *n*¹ surrounding the pivots *n*² of the arms *m*¹ tends to extend the arms *m*¹ to bring them in line with the bracket *m* as shown in dotted lines in Fig. 2. In this position a stop *m*² 70 on one arm *m*¹ bears against the counter stop *m*³ on the bracket *m*. A gripper *o* made of resilient material such as steel is connected to the free end of the bracket *m* 75 for the purpose of casting off the paper 80 from the type plate when printed.

Above the type plate *a*, which is in position for printing, and in the path of the pressure roll *n* is an inking ribbon *p* and on the latter is placed the paper, envelop or the like to be printed. On rotating the shaft *h* the pressure roll *n* revolves about the axis of the shaft and when it comes into its lower position it strikes the paper to be printed 85 and rolls thereon with a suitable pressure, the arms *m*¹ being turned to a certain angle with respect to the bracket *m*. When the print is finished the article printed is removed by the gripper *o*. As shown in Fig. 90 2, the gripper bears on the roll *n* so that the 95

- position of the gripper is so controlled by the roll that it will not come into contact with the printed article until the roll has passed over the printing plate. As the arms 5 m' are extended by the spring n' , as above described, the gripper o , which extends beyond the roll n , will come into engagement with the printed article, and to prevent smutting, said article is raised from the plate 10 immediately after the roll has passed over the latter as will be hereinafter described. Evidently the type plate should not be moved during printing and therefore the movement of the chains d must be intermittent. To enable this, the bevel gear k^2 on 15 the shaft k is mutilated as before stated, so that the shaft l is only rotated, when the toothed part of the gear k^2 engages the gear k^3 .
- 20 Should it be desired to make a number of prints from the type plate lying in the path of the pressure roll n the chains d must be stopped altogether and for this purpose the clutch k^1 is provided, which will be thrown 25 out of gear when several prints are to be made from the same type plate.
- The type plate after being used in the manner described above will be moved farther on by the chains d and finally cast on 30 to the sloping guide plate q , which leads the type plates to a gathering shaft or tube b^1 . To secure a proper piling up of the type plates in this tube care is taken to give the type plates the same amount of drop. For 35 this purpose a movable carrier plate r is provided which projects into the shaft b^1 which is open on one side. The carrier plate r is fastened to a chain s running over two sprocket wheels s^1 , which may be driven by 40 any convenient means for instance by a worm wheel t carried by the upper sprocket wheel and a worm t^1 fastened to the shaft k . The number of teeth of this gearing is so chosen, that on each movement of the 45 chains d the carrier plate r is moved downward the thickness of one type plate.
- At the place where the printing is carried on, a frame u is arranged in openings u^1 provided in the table c . This frame u is 50 carried by vertical rods v and held by spiral springs w in its normal position, that is to say in such a position, that the upper side of the frame slightly projects above the printing surface of the types. In this position the frame u prevents the printed paper 55 from being pressed against the ink ribbon by the gripper o and thus from being smuttied. The springs w yield under the pressure of the pressure roll n .
- 60 During the movement of the type plates along the table the frame must be in its lower position. To carry out this lowering, the rods v at their lower end are connected with a cross bar x , which is engaged by a 65 wedge shaped slide y , guided on a plate y^1 ,

attached below the table c . By a lever system y^2 the slide y is in operative connection with a block or roller y^3 , which is engaged by a cam z , fixed on the tube i . Thus by rotating the tube i the roller y^3 will be 70 moved in longitudinal direction with respect to the shaft k and the slide y will be reciprocated correspondingly. The shape of the cam z is such that the frame u will be held below the table c during the movement of the chains d . The ink ribbon p is fastened in usual manner to two rollers 1 and 2, which may be rotated in any known manner to wind the ink ribbon from one roller to the other. The means for guiding and 80 operating the ink ribbon are so well known, that it is unnecessary to illustrate them.

The use of the circulating pressure roller n has the advantage that the printing is executed very quickly and that every type 85 is printed with sharp and distinct lines.

I claim:

1. In a printing machine, a type plate support, an extensible carrier revoluble in a vertical plane transversely to the support, 90 a pressure roll mounted in the carrier, means on the latter to yieldingly press the roll onto a type-plate mounted on the support, a yielding paper support surrounding a type plate positioned below the carrier and 95 adapted to be depressed by the roll, and a resilient member on the carrier adapted to engage articles on the support.

2. In a printing machine, a type plate support, an extensible carrier revoluble in 100 a vertical plane transversely to the support and having a spring actuated hinged end portion, a pressure roll rotatably mounted in the latter, a yielding paper support adapted to surround a type plate and de- 105 pressible by the roller, a resilient arm mounted on the carrier and extending beyond the roller, and means to raise the support into the path of said arm.

3. A printing machine for minor printings having means for feeding type plates 110 to a printing place, a pressure roll adapted to move in a circle and to roll over the paper to be printed when placed on the type plate, a shaft, a bracket mounted on the 115 shaft, two arms rotatably attached to the bracket, and a spring adapted to hold the arms in a line with the bracket, the pressure roll being journaled between the said arms.

4. A printing machine for minor printings having means for feeding type plates 120 to a printing place and a pressure roll adapted to move in a circle and to roll over the paper to be printed when placed on the type plate, a shaft, a bracket mounted on the 125 shaft, two arms rotatably attached to the bracket, a spring adapted to hold the arms in a line with the bracket, the pressure roll being journaled between the said arms, and a gripper attached to the bracket and adapt- 130

ed to remove the printed material from the type plate when the pressure roller has passed over the same.

5. A printing machine for minor printings having means for feeding type plates to a printing place, a pressure roll adapted to move in a circle and to roll over the paper to be printed when placed on the type plate, a carrier arm for the pressure roll adapted 10 to yield during the working of the roll, a

gripper attached to the carrier arm, a frame adapted to embrace the type plate in its printing position, and means adapted to lower the plate during the printing operation and to raise it when the gripper engages the printed article.
